(57) **CLAIM**

The ornamental design for a tablet case, as shown and described.

DESCRIPTION

FIG. 1 is a front side perspective view of a tablet case opened showing my new design;

FIG. 2 is a front elevational view of the tablet case of FIG. 1;

FIG. 3 is a rear elevational view of the tablet case of FIG. 1;

FIG. 4 is a top plan view of the tablet case of FIG. 1;

FIG. 5 is a bottom plan view of the tablet case of FIG. 1;

FIG. 6 is a left side elevational view of the tablet case closed;

FIG. 7 is a right side elevational view of the tablet case closed;

FIG. 8 is a front perspective view of the tablet case, depicting a flap in an open position; and,

FIG. 9 is a rear perspective view of the tablet case, depicting a flap in an open position.

The broken lines representing stitching are part of the claimed design.
